UNITED STATES PATENT OFFICE.

RAYMOND CORDEUX WETHERELL, OF SLOUGH, ENGLAND.

DIFFERENTIAL AXLE.

1,241,457.

Specification of Letters Patent. Patented Sept. 25, 1917.

Application filed November 23, 1915. Serial No. 68,102.

To all whom it may concern:

Be it known that I, RAYMOND CORDEUX WETHERELL, a subject of the King of England, residing at Hautley, High street, 5 Slough, in the county of Bucks, England, have invented certain new and useful Improvements in Differential Axles, of which the following is a specification.

This invention relates to differential driving axles adapted for use in connection with power driven vehicles, such as motor cars, tractors and the like.

The object of the invention is to provide means for allowing the speed of the axle 15 wheels, when on a curve, to differ according to the distance covered by each wheel in the same period of time, and the construction is of that type in which this differentiation is obtained by employing a central driving disk 20 receiving the power, and two independent and laterally immovable side disks attached to the road wheels, the power being transmitted by means of convex, round-ended pins, which slide horizontally through holes 25 in the central driving disk, and engage with concave spherically-surfaced countersunk hollows in the opposed faces of the two independent and laterally immovable driven disks attached to the road wheels.

30 The construction is designed to obviate the drawbacks of the ordinary form of differential which drawbacks are evidenced by skidding in motor cars when the propeller shaft brake is suddenly applied, and also 35 by the rapid spinning of one wheel when it is unable to obtain an adhesion on a slippery surface, so that the whole of the tractive effort is dissipated in this spinning wheel, the other wheel remaining stationary 40 and acting as a fulcrum for the first mentioned wheel to spin upon.

The functions of the differential about to be described are as follows:

When the vehicle enters upon a curve, the 45 increased speed of the outer wheel causes the inside wheel to be partially or entirely liberated, and to receive none, or only a part of the driving power, the whole or a major portion of the drive being transmitted 50 through the outer wheel, thus assisting the steering of the vehicle to which the differential is fitted.

In all other circumstances, the new differential causes the axle to act as a solid axle.

55 In order that my invention may be clearly understood, I will now proceed to describe

the same with reference to the accompanying diagrammatic drawings, in which:

Figure 1 is a sectional elevation of a rear axle casing in which is mounted the new 60 differential, parts of which are shown in elevation and others in section.

Fig. 2 is a right hand end view of the female dog clutch member on the left-hand side of *a* in Fig. 1, which member is lettered *f*.

Fig. 3 is a right hand view of the parts lettered *a*, *b*, *m* and *t* in Fig. 1.

Fig. 4 is a right hand end view of a female dog clutch member on the right hand 70 side of *a*, in Fig. 1, which member is lettered *f*.

Figs. 5, 6 and 7 are external elevations of the new differential showing the relative dispositions of the parts under working 75 conditions.

Referring to Fig. 1, it will be seen that the driving crown bevel wheel is bolted to a disk *a*, which has two stub shafts *b*, *b* formed integrally with or otherwise rigidly 80 attached to it.

The ends of the stub shafts *b* are shod with thrust disks *t*, these being intended to distribute the end thrust which arises from the working of the apparatus and also from the bevel drive.

As will be seen, the stub shafts *b* are shown provided with keys but they may be castellated as an alternative if desired.

Upon the shafts *b*, *b*, two peripherally 90 toothed disks or male dog clutch members are free to slide laterally. These members are lettered *m*, *m* and are connected together by means of tie rods *c*, *c*, of the form shown, the ends being riveted into the male dogs 95 and having shoulders, so that the rods *c* are able to transmit the thrust.

The rods *c* pass freely through apertures in the disk *a*, without touching the same.

By this means, the interconnected male 100 dog clutches *m*, *m* are able to reciprocate on the keyed stub shafts *b*, *b*, while turning with the disk *a*.

The foregoing parts form the primary parts of the differential the secondary parts 105 being as follows:

The ends of the half axles of the road wheels are provided with hollow cup-shaped members *f*, *f*, the stems of the cups forming hollow bosses, into which the half axle ends 110 are secured.

The usual journal and thrust ball bearings

are mounted upon the outside of these bosses and also housed in the axle casing as indicated in Fig. 1.

A circular seating is provided in the base 5 plate of each cup into which the thrust disks *t* are stepped.

The circular walls of the cup are cut out in the form of dog teeth, in and out of which the male dogs *m* can slide when reciprocating 10 along the stub shafts *b*.

Attention is here drawn to the form of dog teeth employed. It will be noticed that their surfaces are not horizontal, but slope so that in the case of the female dog teeth 15 the opening between the tooth faces is greater on the side toward the crown bevel disk *a*. Also, the surfaces of the teeth are flat.

The angle of the male dog clutch tooth 20 face is similarly arranged with a flat surface, so that when pressure between the male and female dog tooth surfaces is set up, a tendency is created for the male dog to be forced away from the female dog in the 25 direction of the crown bevel disk *a*. For convenience in description, these male and female dog tooth surfaces are lettered *h* and *g* respectively, and it must be also here mentioned that the angle of slope of the 30 dog teeth has been purposely exaggerated to what would be advisable in practice in order to make the working appear more clear.

The above details can now be condensed or 35 classified into the following two groups:—

The primary group consists of the crown bevel disk *a*, its stub shafts *b*, *b*, thrust disks *t*, *t* and sliding male dogs *m*, *m*, connected together by compression rods *c*, *c*, which 40 primary group is held between the secondary group members consisting of the cup-shaped female dog clutch members *f*, *f*, which mesh with the sliding male dogs *m*, *m*.

The distance between and also the length of the female dogs are such that the male 45 dogs can slide out of mesh with the female on the one side while the other male dog can enter further into engagement with the female on the other side, as shown in Fig. 7.

The method of operation is as follows:—

When the axle is being driven it is assumed that the top of the crown bevel wheel 50 shown in Fig. 1, is moving in a clockwise direction, when viewed from the right hand side of Fig. 1. This causes the sloping surfaces *g* and *h* of the dog teeth to come together as in Fig. 5, and transmit the power to the road wheels.

As long as the axle travels along a straight path, both wheels turn at the same speed, 60 and consequently both the sliding dog clutches *m*, *m*, attempt to move inward, but are prevented from so doing by the compression in the rods *c*, *c*, the result being that *m*, *m* occupy their mid position of 65 travel along *b*, *b*.

Now assume that the axle enters on a curve, and that the clutch on the left-hand side of Fig. 1 is that belonging to the inner wheel.

The right hand wheel, being on the outside of the curve, begins to rotate the quicker, therefore causing the contact between the surfaces *g* and *h* of the right hand clutch to be momentarily broken as shown in Fig. 6. The result is that the whole of 70 the driving pressure is thrown upon the surfaces *g* and *h* of the left-hand clutch, belonging to the inner wheel, with the result that the male clutch on that side is expelled from the female, and the inner wheel becomes free as shown in Fig. 7.

After the inner wheel is free, the whole of the drive is transmitted by the outer wheel clutch, so that the male dog clutch on this side, in its turn, is under the influence of the 80 explosive force of the female clutch, so that its companion endeavors to remesh with its mate.

As, however, the wheels are now revolving at varying speeds, it is evident that a 90 certain period must elapse before the teeth of the left-hand clutch are in the proper position to effect this, and in the meantime there will be a certain amount of friction between the vertical faces in juxtaposition 95 of the left-hand male and female dogs, which tends to transmit a portion of the drive to the left-hand wheel, this tendency being increased by the act of remeshing when it occurs.

After this, if the wheel is still on a curve, the cycle of operations is continued as before.

It should here be mentioned that any convenient number of dog teeth can be employed, the arrangement not necessarily being limited to the four here shown.

What I claim as my invention and desire to secure by Letters Patent of the United States of America is:—

1. In a differential axle for motor vehicles, the combination of a driving member provided with stub axles, one on each side thereof, two plates, one located on each side of the driving member, tie rods connecting 115 together said plates and passing through appropriate apertures in the driving member, the element constituted by the said plates and the tie rods rotating with the stub axles while being free to move longitudinally with respect thereto, said plates having peripherally arranged teeth, said teeth having flat inclined surfaces at the sides and plane surfaces at the ends, and other plates carrying the ordinary half 125 axles, and provided with correspondingly shaped teeth having inclined surfaces at the sides and plane surfaces at the ends, the last mentioned plates being at such a distance apart that the element constituted by the 130

first mentioned plates and tie rods can slide into such a position that when the teeth on one of the first mentioned plates are fully in engagement with those on the plate in connection with the corresponding axle, those on the other first mentioned plate are entirely disengaged from the other last mentioned plate, for the purposes set forth.

2. In a differential axle for motor vehicles, the combination of a driving member provided with stub axles, one on each side thereof, thrust disks at the ends of the said axles, two plates, one located on each side of the driving member, tie rods connecting together said plates and passing through appropriate apertures in the driving member, the element constituted by the said plates and the tie rods rotating with the stub axles while being free to move longitudinally with respect thereto, said plates having peripherally arranged teeth, said teeth having flat inclined surfaces at the sides and plane surfaces at the ends, and other plates carrying the ordinary half axles and provided with seatings for the accommodation of the before mentioned thrust disks and with teeth corresponding in shape to those on the plates forming part of the aforesaid element, the last mentioned plates being at such a distance apart that the element constituted by the first mentioned plates and the tie rods can slide into such a position that when the teeth on one of the first mentioned plates are fully in engagement with those on the plate in connection with the corresponding axle, those on the other first mentioned plate are entirely disengaged from the other last mentioned plate, for the purposes set forth.

3. In a differential axle for motor vehicles, 40 the combination of a driving crown bevel wheel having a disk attached thereto, stub axles, one on each side thereof, two plates, one located on each side of the said disk, tie rods connecting together said plates and 45 passing through appropriate apertures in the said disk, the element constituted by the said plates and the tie rods forming keys and key-ways and rotating with the stub axles, 50 while being free to move longitudinally with respect thereto, said plates having peripherally arranged male dog teeth, said teeth having flat inclined surfaces at the sides and plane surfaces at the ends, thrust disks at the ends of the stub axles, and other 55 plates carrying the ordinary half axles and provided with seatings for the accommodation of the before mentioned thrust disks and with female dog teeth corresponding in shape to those on the before mentioned plates, the last mentioned plates being at such a distance apart that the element constituted by the first mentioned plates and the tie rods can slide into such a position 60 that when the teeth on one of the first mentioned plates are fully in engagement with those on the plate in connection with the corresponding axle, those on the other first mentioned plate are entirely disengaged 65 from the other last mentioned plate for the 70 purposes set forth.

In testimony whereof I affix my signature in presence of two witnesses.

RAYMOND CORDEUX WETHERELL.
